CARD HOLDER

Lloyd L. Wells, Honeoye Falls, N. Y.

Application March 22, 1934, Serial No. 716,852

3 Claims. (Cl. 248—33)

This invention relates to a card holder, and has for its purpose to afford a practical construction that can be manufactured at a low cost, and can be variously used in grocery and other stores for retaining and displaying cards, price tags, or the like.

One object of the invention is to afford a structure which can be located on a counter or on any kind of support such as the goods or packages on sale without in any way damaging or affecting them, and which will effectively hold and display a card or tag.

A further object of the invention is to afford a construction that is not likely to tilt over or fall, so that when once positioned, the card will remain in the desired upright position, and also one in which the card can readily be inserted or removed.

To these and other ends, the invention consists in the construction and combination of parts that will appear clearly from the following description when read in conjunction with the accompanying drawing, the novel features being pointed out in the claims following the specification.

In the drawing:

Fig. 1 is a side elevation of a preferred embodiment of the invention, illustrating a card in position;

Fig. 2 is a plan view, and

Fig. 3 is a side elevation, looking in a direction opposite to that of Fig. 1, the base appearing in section.

Referring more particularly to the drawing, in which like reference characters refer to the same parts throughout the several views, 1 designates a base or support that is constructed preferably of lead, although it may be of other suitable metal or material to afford a relatively heavy or weighted body having such relation to the card and card retaining portion that they will maintain ordinarily a normal upright position and are not likely to tilt over or fall to one side, which is extremely important in a device of this character.

Attached to the base 1 is a card retaining element which is preferably constituted by a wire member bent upon itself, and preferably coiled circularly to afford two or more adjacent convolutions between which a card may be slipped and held. The coil card retaining portion is designated at 2, while 3 and 4 designate the ends of the wire member which are preferably arranged in spaced substantially parallel relationship, as shown.

The ends 3 and 4 extend through openings in the base 1 and are embedded therein, the base 1 when made of lead being cast around the ends 3 and 4, although the latter may be otherwise suitably attached to the base if preferred. It has been found that economical and practical re-

sults are attained by embedding the ends 3 and 4 in a lead base cast about the same, the ends preferably extending from the top to the bottom of the base and being spaced from each other so as to afford a rigid connection between the base and the card retaining element.

Where the convolutions of the coil lie opposite each other, it may sometimes be difficult to insert a card therebetween, and in order to insure quick and ready positioning of a card, the end 4 is made longer than the end 3 so as to extend across the circular coil, the uppermost extremity of the straight end 4 extending slightly beyond the adjacent convolution of the coil, as indicated at 5. This affords a projecting corner under which a card can be positioned and thus readily inserted between the end 4 and the adjacent portion of the coil, or the card can likewise easily be inserted by positioning it against the straight end 4 under the latter and between it and the adjacent portion of the coil, and then by pushing the card laterally, it assumes the position shown in Fig. 1. Where the card is inserted at the top and moved downwardly, it occupies a position in engagement with the bottom of the circular coil, above the position illustrated in Fig. 1.

The term "lead", as used throughout the specification and claims, is intended to comprehend any alloy or composition material that can be flowed and cast around the ends of the wire member.

While the invention has been described with reference to the details shown, it is not confined to this precise arrangement, and the application is intended to cover such other changes or departures as may come within the purposes of the improvement or the scope of the following claims.

I claim:

1. A card holder comprising a lead base, and a wire member including a card retaining coil portion, the ends of the wire member being arranged in spaced substantially parallel relationship and embedded in the base.

2. A card holder comprising a lead base, and a wire member including a circularly coiled card retaining portion and spaced substantially parallel ends extending through and embedded in the base, one of said ends extending across a portion of the circularly coiled portion and affording means for permitting ready insertion of a card between adjacent convolutions of the coiled portion.

3. A card holder comprising a lead base, and a wire member including a circularly coiled card retaining portion, the ends of the wire member being arranged in spaced substantially parallel relationship and embedded in said lead base.
